UNITED STATES PATENT OFFICE.

HARRY F. WAHR, OF WEST HOMESTEAD, PENNSYLVANIA.

PICKLING MACHINE.

Application filed May 25, 1926. Serial No. 111,523.

The present invention relates broadly to the art of cleaning scale from annealed sheets or the like, and more particularly to an improved pickling machine adaptable for use in the pickling of miscellaneous metal products whether of ferrous or non-ferrous nature.

At the present time it is customary in the art to which the present invention relates to provide a plurality of baskets or carriers so mounted as to permit the same to be vertically reciprocated in such manner that the articles or sheets carried thereby may be subjected successively to baths of different characteristics. Ordinarily the operation necessitates the use of one or more acid baths followed by a rinsing bath in water and in some cases a further treatment with an alkaline solution in the event the pickled material is to be held for future treatment.

Customarily the baskets or other carriers containing the material to be treated have been reciprocated vertically by means of fluid pressure, either steam or air being ordinarily utilized. This operating fluid has been permitted to exhaust into the atmosphere during the entire operation, thereby necessitating either a comparatively large air compressor to furnish the necessary amount of compressed air or requiring the wasting of a considerable amount of steam.

It has also been customary in the art to effect the desired vertical movement of the baskets or carriers entirely from a central ram or support. Due to the fact that the support cannot continuously support uniformly loaded carriers, it will be apparent that the structure of the pickling machine is unbalanced during normal operation thereof. This unbalanced condition is transmitted to the central ram or support in such manner that non-uniform wearing thereof and other parts has resulted.

It has heretofore been proposed to construct pickling machines of a counter-balanced type wherein the repeated exhausting of the operating fluid has been rendered unnecessary and to effect the pickling reciprocations by means of mechanical power devices. In such constructions, however, not only has it been customary to overbalance the weight of the apparatus by means of the air whereby an actual pulling down has

been performed by the mechanical power devices but the power has been so applied as to result in non-uniform wear.

The present invention has for certain of its objects the provision of an improved apparatus in which the operating load is more nearly balanced during the operation of the machine whereby uniform conditions of wear are insured.

Still another object of the invention is to provide a construction which may be operated while only partially counterbalanced by air pressure, or other operating fluid, in such manner that the machine tends to return by gravity to a predetermined position, the reciprocation in the opposite direction being obtained by an independent power device.

Still a further object of the invention is to provide a construction in which the independent power device need not be mechanically connected to the machine, but which cooperates with the machine in such manner that a centering operation is obtained.

In the accompanying drawings there are shown for purposes of illustration only, certain preferred embodiments of the present invention, it being understood that the drawings do not define the limits of my invention as changes in the construction and operation disclosed therein may be made without departing either from the spirit of the invention or the scope of my broader claims.

In the drawings,

Figure 1 is a diagrammatic top plan view illustrating one arrangement of pickling machine constructed in accordance with the present invention,

Figure 2 is a view similar to Figure 1 illustrating another embodiment of the invention,

Figure 3 is a vertical sectional view on an enlarged scale on a line III—III of Figure 2, and

Figure 4 is a view similar to Figure 3 illustrating another embodiment of the invention.

Referring to the form of invention illustrated diagrammatically in Figure 1, there is indicated a base 2 from which a main support or ram 3 projects upwardly. This ram is provided at its upper end with a

superstructure in the form of a spider comprising a series of equi-distantly spaced outwardly projecting radial arms 4. Each of these arms is of such construction that it 5 is adapted to have suspended therefrom a basket or carrier 5 for cooperation with vats 6 and 7, respectively. In the normal operation, the ram 3 and the superstructure are rotated to carry one of the baskets from 10 the loading platform 8 to a position over the acid vat 6. In this position the carrier is lowered into the acid vat and subjected to agitation therein by the reciprocation of the superstructure. After a predetermined 15 time interval the superstructure is lifted and then rotated to bring the carrier from the acid vat 6 to the water vat 7. This same operation carries a fresh basket from the loading platform to the vat 6. The operation 20 is repeated successively, whereby the articles supported by the baskets or carriers are effectively cleaned and rinsed.

In Figure 2, a similar structure is illustrated, the superstructure in this instance, 25 however, comprising four arms 4' and three vats 6', 7' and 9. The operation is similar to that previously referred to with the exception that the vats 6' and 7' may both contain acid, or the vats 7' and 9 may both 30 contain water, or the vat 6' may contain acid, the vat 7' water and the vat 9 an alkali solution, or any other usual or well known arrangement may be utilized.

With both forms of the invention referred 35 to it will be apparent that due to the fact that one of the arms at all times cooperates with the loading platform and while in such position may have either an empty carrier or no carrier thereon, the load is not equally 40 distributed on the superstructure. This unequal load distribution tends, in existing machines, to pull the support or ram 3 laterally in such manner as to subject it and other parts to uneven wear. In accordance with 45 the present invention, this objectionable tendency is entirely obviated by providing on the superstructure a plate 10 of suitable construction having on its under side, as clearly shown in Figure 3, a plurality of 50 depressions 11 preferably presenting continuously and uniformly curved surfaces. These depressions are located a substantial distance from the axis of rotation of the machine, the distance being such that by 55 providing power means 12 positioned substantially as indicated in the drawings, a lift may be imparted to the structure at substantially the center of gravity of the loaded machine. In this manner compensation is 60 effected for uneven load distribution, and uneven wear on the ram 3 and other parts is avoided.

As illustrated in Figure 3 of the drawings, the base 2 may be of such construction 65 as to provide a downwardly extending

cylinder 13 and laterally projecting supporting platforms 14. Mounted on one of the platforms 14 may be an electric motor 15 having a suitable gear connection 16 to a crank shaft 17. The crank arm 18 of this shaft may be connected by a pitman 19 to a plunger 20 guided by the cylinder 21. By reason of this construction it will be apparent that as the motor 15 rotates, the plunger 20 will be alternately raised and lowered. In actual practice, the motor is preferably substantially enclosed within the base 2, thereby protecting the same from the corrosive action of the fumes from the acid baths. The central plunger 3 extends from substantially the bottom of the cylinder 13 to the superstructure which it carries. At a point intermediate its length, the ram carries a piston 22 for cooperation with a cylinder 23. The cylinder 23 has a supply line 24 communicating with the same below the piston 22 by reason of the passages 25, and a second fluid line 26 communicating with the same above the piston 22. These lines are provided respectively, with control 90 valves 27 and 28 respectively. The cylinder 13 likewise has a connection 29 to the lower end of the cylinder 21, this connection being controlled by valve 30.

In operation, fluid pressure is supplied to 95 the lines 24, 26 and 29, whereby the lower end of the ram 3 and the bottom of the piston 22 and the lower end of the plunger 20 are all subjected to air pressure effective for counter-balancing the weight of the machine 100 while the upper side of the piston 22 is subjected to the same pressure conditions acting in opposition to the counter-balancing action and having an effective tendency toward lowering the ram. It will be apparent that a 105 differential pressure action is exerted on opposite sides of the piston 22, the pressure effective for counter-balancing being greater than the pressure effective for moving the ram downwardly due to the fact that the 110 lower end of the ram 3, is open to pressure within the cylinder 13. This differential pressure coupled with the balancing pressure exerted on the lower end of the plunger 20 bears a direct relation to the normal 115 weight of the apparatus, and is preferably such that with all of the air connections open the apparatus will normally tend to assume its lower position as shown in Figures 3 and 4 of the drawings. At this time, 120 operation of the motor 15 will be effective through the plunger 20 for producing a series of vertical reciprocations of the superstructure and the baskets supported thereby. Due to the substantial counter-balancing of 125 the weight of the machine, the motor 15 may be extremely small as its load will be comparatively negligible. Also, since this load is directly applied to the superstructure independently of the ram 3 and at a point sub- 130

stantially coincident with the center of gravity of the loaded machine, frictional resistance and wear are both reduced to a minimum.

5 When it is desired to raise the machine to permit rotation of the carriers from one vat to another, the valve 28 is turned whereby the interior of the cylinder 23 above the piston, is opened to the atmosphere through the 10 connection 28' and communication between the line 26 and the cylinder cutoff. In this manner, each lifting operation of the superstructure for transfer purposes may be obtained by merely operating the valve 28 and 15 will only involve the loss of the fluid contained within the cylinder 23 above the piston, the normal operation of the machine by reason of the motor 15 being obtained without loss of fluid pressure. While the superstructure is in elevated position it will be 20 clear of the plunger 20, thereby permitting rotation as required to bring a treated load of material to the loading platform and a new load of material to the first vat. Thereafter, upon returning the valve 28 to its original 25 position, the weight of the machine will be such that it will lower by gravity into engagement with the plunger 20. The upper end of the plunger 20 preferably has a radius 30 of curvature slightly less than the radius of curvature of the recess 11, whereby substantially a universal joint is provided between the superstructure and plunger of such 35 nature that torsional strains are not transmitted to the plunger. Also, the character of the engaging surfaces of the plunger and recesses are such that the parts tend to automatically center themselves as will be apparent.

40 It will be apparent to those skilled in the art that a machine of the general character herein contemplated must be adaptable for handling loads, the total weight of which varies over a considerable range. Where 45 comparatively heavy loads are being handled, the pressure conditions existing in the cylinders 13, 21 and 23 will be comparatively high whereby the differential between the cylinders 13 and 23 will be sufficient to effect 50 the desired lifting. With lighter loads, however, a differential of the character referred to might be great enough to prevent lowering of the parts. In such cases the pressure supplied to the cylinders may be decreased 55 by the use of a pressure reducing valve until a point is reached at which the desired amount of counter-balancing is exactly obtained.

60 In some cases it may be desirable to provide a more accurate or sensitive counter-balancing than is obtained by the differential between the cylinders 13 and 23. In such cases the valve 30 in the form shown in Figure 3 may be constructed as a pressure reducing valve whereby some slight varia-

tion in pressure may be obtained in the cylinder 21. If desired, there may be provided a construction as shown in Figure 4 in which a supplemental source 31 of fluid under pressure may be provided for the cylinder 21. 70 This source will then be available for supplying to the cylinder any desired pressure condition either greater or less than that in the rest of the system, whereby the cylinder 21 will operate as a comparatively fine adjustment from a counter-balancing standpoint while the differential between the cylinders 13 and 23 will give an approximate counter-balancing. By slightly under counter-balancing at all times, irrespective of 80 load, no mechanical connection between the plunger 20 and the superstructure is required, and consequently no strains are transmitted to the superstructure by the motor during the gravity descent of the parts. 85

With apparatus of the character heretofore available in which the lifting has been accomplished by a central cylinder, it has been necessary to provide some mechanical tie, usually in the form of a chain, to prevent 90 gradual creeping of the superstructure. With the construction of the character herein contemplated, any creeping is entirely prevented by reason of the engagement between the plunger 20 and the depressions 11, whereby the parts are held in central position at 95 all times.

It will be understood that it is desirable in all installations of the general character referred to to prevent unnecessary jar to the 100 parts such as would result from a mechanical engagement between the piston 22 and the lower end of the cylinder 23. The plunger 20, will, therefore, preferably be so constructed that at the limit of its downward 105 movement there is sufficient clearance between the underside of the piston and the bottom of the cylinder to prevent undue shock.

With the construction disclosed, in which 110 a pressure differential is utilized, it is only necessary to provide a single stuffing box 32 for the ram 3. This is true for the reason that the lower end of the cylinder 13 may be permanently closed and for the reason that 115 air passage between the cylinder 13 and the cylinder 23 is permitted. At the same time, even with the use of a single stuffing box, the ram is effectively guided by its bearing in the stuffing box and its bearing provided 120 by the piston 22.

In the normal operation of the machine of the nature referred to, about ninety percent of the operating time is devoted toward 125 reciprocation by means of the motor 15 and ten percent of the time to lifting and turning. Assuming approximately thirty reciprocations per minute and an operating period of nine minutes, it will be apparent that two hundred seventy reciprocation are ob- 130

tained without the loss of any fluid under pressure. Thereafter, by merely exhausting the cylinder 23 once, the desired lifting of the superstructure may be obtained. Inasmuch as this exhausting involves only the loss of a small amount of fluid and inasmuch as it occurs at comparatively wide intervals throughout the operation of the machine, it will be apparent that a very small compression will provide the necessary fluid under pressure for operating the parts, or that only a small amount of steam will be required in the event steam is used.

Certain advantages of the present invention arise from the provision of a counterbalanced pickling machine with independent power operated means for reciprocating the same and effective only for lifting the machine.

Other advantages arise from the provision in a machine of the character referred to, of means whereby the effective counter-balancing action may be varied at will.

Still other advantages of the invention arise from the provision of a differential piston structure adapted to have both sides subjected to the same pressure with the result that the total pressure on one side is greater than the total pressure on the opposite side.

Still further advantages arise from the provision of an independent power operated mechanism effective substantially at the center of gravity of a loaded machine as well as from the provision of a construction such that automatic centering of the parts is obtained without the necessity of any mechanical connection between the power devices and the superstructure.

I claim:

1. In a pickling machine, a supporting frame, counter-balancing means for said frame, an operating ram for said frame, and independent mechanical means for effecting movement of said frame in one direction only.

2. In a pickling machine, a supporting frame, a support therefor, a plurality of carriers on said frame substantially equidistantly spaced from said support and means effective at one side of said support and substantially at the center of gravity of said frame when loaded for producing movement thereof.

3. In a pickling machine, a supporting frame, a lifting plunger for said frame, and reciprocating means for said frame cooperating therewith at substantially its center of gravity when loaded and effecting movement of said frame in a manner similar to the movement effected by the moving of said plunger.

4. Lifting means for pickling machines comprising a superstructure, a plurality of carriers thereon, and means engaging said

superstructure at substantially its center of gravity when loaded with one empty carrier for simultaneously lifting said superstructure and all of said carriers.

5. Lifting means for pickling machines comprising a superstructure, and means engaging said superstructure at substantially its center of gravity when loaded for effecting movement thereof in one direction only.

6. In a pickling machine, a superstructure, a guiding ram therefor, and means abutting against the under side of said superstructure at substantially its center of gravity when loaded with one empty carrier for lifting the superstructure.

7. In a pickling machine, a superstructure, a ram carrying said superstructure, a piston, connections for subjecting opposite sides of said piston to the same pressure, said piston having a differential area effecting on opposite sides, and lifting means operating with said piston.

8. In a pickling machine, a carrier frame, means for under counter-balancing said frame, and means effective in an upward direction only for lifting said frame, said means having an abutting engagement with said frame, substantially coinciding with the center of gravity of the frame when loaded with one empty carrier.

9. In a pickling machine, a supporting ram, a cylinder into which said ram extends, a piston on said ram working within said cylinder and having its opposite sides normally connecting with a source of fluid under pressure while maintaining the ram in its lower position, and means for releasing pressure from one side of said piston to effect upward movement of the ram.

10. In a pickling machine, a superstructure, a ram supporting said superstructure, means for delivering fluid under pressure to opposite portions of said ram for establishing a differential pressure condition correlated to the weight of the superstructure whereby the superstructure will normally gravitate to a lower position, and means for the restricting of the delivery of fluid to one portion and thereby increasing the pressure differential at will for effecting movement of the superstructure in the opposite direction.

11. In a pickling machine, a superstructure, a ram supporting said superstructure, means for delivering fluid under pressure to opposite portions of said ram for establishing a differential pressure condition correlated to the weight of the superstructure whereby the superstructure will normally gravitate to a lower position, and means for the restricting of the delivery of fluid to one portion and thereby increasing the pressure differential at will and for also releasing the pressure at a predetermined point.

12. In a pickling machine, a carrier

frame, means for under counterbalancing when loaded, and for raising said frame, and other means effective in an upward direction only for lifting said frame.

5 13. In a pickling machine, a carrier frame, means for under counterbalancing when loaded and for raising said frame, and

other means effective in an upward direction only for lifting said frame, said last mentioned means having abutting engagement with said frame. 10

In testimony whereof I have hereunto set my hand.

HARRY F. WAHR.
